UNITED STATES PATENT OFFICE.

ALBERT JEAN DUCAMP, OF VERSAILLES, FRANCE.

CARBURETOR.

Application filed March 14, 1923, Serial No. 625,058, and in France January 24, 1923.

This invention relates to means for producing, as completely as possible, an emulsion of air and fuel in the carburetor of explosion or internal-combustion engines, and has for its object to supply an emulsion composed of extremely fine drops suspended in air, and further to enable the mixture to be adjusted to the most favourable proportions to obtain perfect combustion.

In existing carburetors, the proportioning of the mixture of air and fuel, for example petrol, is easily effected up to a certain point, but the chief defect is in connection with the subdivision of the fuel into fine drops when the engine is running at a low angular velocity and developing a high torque, particularly in direct drive up-hill, the throttle valve being wide open. Under these conditions, the velocity of the air in the choke tube round the orifice of the jet spray nozzle is insufficient to atomize the petrol properly, and in order to obtain anything like satisfactory results, it is necessary to employ a richer mixture, with a consequent waste of fuel and soot of the cylinders through the incomplete combustion of the insufficiently atomized fuel.

According to the present invention these drawbacks are obviated by preparing a preliminary emulsion of fuel and air, causing this emulsion to flow into a stream of either fuel or air, thus forming a second emulsion, of an extremely finely divided character, before mixing this two stage emulsion, with air drawn in through the choke tube of the carburetor.

The accompanying drawings illustrate, by way of example, two forms of carburetors for carrying out this method, Figure 1 being a vertical axial section showing the invention applied to a carburetor of the type disclosed in French Patent No. 467,541. Figure 2 a cross section on the line 2—2 of Figure 1,

Figure 3 is a similar section, showing a modified construction, and

Figure 4 is a partial section through the carburetor, showing another modification in the arrangement of the air and fuel auxiliary passage.

The carburetor shown in Figures 1 and 2 comprises, the duct *b* leading from the float chamber (not shown), a vertical connecting passage *a* terminating in a wider passage *c* which opens into the choke tube *d* of the

carburetor. Air is admitted to the passage *c* through orifices *e*, *e'*, annular spaces *f*, *f'* and horizontal passages *g*, *g'*. In comparison with this known arrangement, the invention is distinguished by the fact that a passage *h* extends from the intake wall *i* of the passage *a* and opens at *j* into the terminal portion of the annular air intake *f'*.

According to the invention, the portions *k* and *l* are very short, and therefore, the friction on the fuel is less than if *a* and *h* had all along the small sectional area of *k* and *l*. Consequently for a given area, the flow and velocity of the fuel will be greater.

At low engine speeds, the fuel in *j* under the pressure of the level in the float chamber, encounters the air entering through the orifices *e*, *e'* and the spaces *f*, *f'*, and produces a preliminary emulsion. This latter then flows, through the horizontal passages *g*, *g'* into the passage *c* and encounters the vertical stream of fuel issuing from the passage *a*. This produces, therefore, a second emulsion, richer in fuel and in an extremely fine state of division, which mixes, at the outlet of the passage *c*, with air drawn in through the choke tube *d*.

The more the speed of the engine increases, the more rapid the flow of fuel through the wall *i* and the smaller the volume of fuel delivered by the passage *h*.

At high speeds the partial vacuum set up in the intake portion *i* of the passage *a* exceeds the pressure due to the fuel level in the float chamber. The current is reversed in the passage *h*, which then supplies air coming in through the space *f*.

The air emulsifies the fuel below the part *i*, and this emulsion is delivered by the passage *a*, and on entering the passage *c* meets another portion of the air coming from the space *f'* and issuing by way of the passages *g*, *g'*. A second emulsion of extremely minute drops, is formed in the passage *c* and mixes, at the outlet of this passage, with the air drawn in through the choke tube *d*.

In this second method of operating, the mixture is poorer than in the former stage, and it is precisely at high speeds that it is necessary to employ a poorer mixture.

On the other hand, the quality of the mixture may be varied at low speeds as in the case of high speeds, by modifying the relative diameters of the constricted sections of the passages *h* and *a*. In this manner a

suitable adaptation of the device can be obtained for engines and motor cars of any type whatsoever.

The passage *h* therefore performs the dual role of a compensator, by supplying fuel at low speeds, and of a restrictor, by supplying air at high speeds.

In applying the invention as represented in Figure 3, the fuel intake passage *a* is connected by passages *b* and *m* with the fuel float chamber in the usual manner. Instead of issuing round the orifice of the passage *c* in the choke tube *d*, air entering by way of the passage *n* and space *f* is shut off at 15 *o* and passes into the passage *a* and the passages *b*, *c* by way of the auxiliary passage *h* and the passages *g*, *g'*, by means of an arrangement analogous to that shown in Figures 1 and 2. The method of operating, 20 as regards the circulation of air and fuel round the passages *a* and *h* is analogous in every respect to the operation of the preceding form of the invention and the same letters of reference denote the passages dis- 25 charging the same functions.

As shown in Fig. 4, the entrance to the compensating passage *h* may be more or less remote from the entrance of the passage *a*. The space *f'* may, for example, be connected 30 with the passage *b* by means of a passage *r*, although, in general, the arrangement according to Figure 1 seems preferable.

The invention may, of course be applied to various types of carburetors.

35 Small ports *t* are provided at the upper

part of the casing *s* of the atomizer; six of such ports for instance or any suitable number may be arranged round the periphery thereof. The air entering the passage *c* and turning round the end portion of the casing *s* in the direction of arrow A causes a partial vacuum above the upper opening of the ports *t*. Air is thus drawn into ports *t* in the direction of arrow B (see Fig. 1) with a certain velocity, and issuing from *t* above 45 the opening *u* of the casing, strikes the jet flowing out of the passage *c*, thus causing a still greater division of the emulsion.

What I claim is:—

An atomizer for a carburetor including a 50 choke tube, a main fuel passageway of comparatively large bore opening at all times at one end into said choke tube and having a single constricted portion intermediate its length, and a tube of larger diameter than 55 said passageway arranged coaxially thereabout, said tube being freely open to atmosphere at one end but closed at the other end with the exception of a compensating duct opening into said passageway at a point be- 60 tween the constricted portion and the inlet of said passageway, the wall of the passageway having a small port extending there- 65 through and opening into the latter at a point between the constricted portion and the outlet of the passageway.

In testimony whereof I hereunto affix my signature,

ALBERT JEAN DUCAMP.
